UNITED STATES PATENT OFFICE

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND

FLEXIBLE STRAP, BAND, OR LINKAGE

Application filed October 23, 1928. Serial No. 314,486.

This invention relates to improvements in flexible metal straps, bands or linkages for use in the manufacture of bracelets, chains, belts and other articles of jewelry or like nature.

One object of the invention is to provide a device of the type specified having relatively flat link-units or chain-elements connected together in articulated relation to adapt the strap, band or linkage to flex readily to fit the contour of the wrist or other part of the body on which it is worn.

Another object of the invention is to provide a device of the type specified in which the link-units or chain-elements are smoothly joined together without disclosing unsightly seams, and which may be flexed to a considerable extent without revealing open joints.

Another object of the invention is to provide a device of the type specified in which the link-units or chain-elements are of box-like construction and joined together by connecting-links which are entirely concealed from view.

Further objects of the improvement are set forth in the following specification which describes a preferred form of construction of the invention as illustrated by the accompanying drawings. In the drawings:

Fig. 1 is a perspective view illustrating the improved strap, band or linkage adapted for use as a bracelet and having clasps at its ends for attaching it to the bails of a wrist-watch; Fig. 2 is an enlarged bottom plan view of a section of the improved strap, band or linkage;

Fig. 3 is a still further enlarged side view of a section of the same;

Fig. 4 is an enlarged sectional view of the strap, band or linkage taken on line 4-4 of Fig. 2;

Fig. 5 is a perspective view of the connecting-link which joins the box-like elements of the strap, band or linkage; and

Fig. 6 is a perspective view of the box-link showing it in inverted position or bottom side up.

The present improved strap, band or linkage has the general appearance of a series of flat, oblong blocks arranged in abutting rela-

tion and having an unbroken surface on the top and sides devoid of any indication of the mechanical means which connect the parts together. The linkage comprises a plurality of elements of two different forms alternating in series, the main link-element 2 being constructed from a sheet-metal blank folded into box-like shape as shown in Fig. 6.

The box-link 2 has a flat top 3 of relatively narrow width, sides 4 bent at right-angles thereto and folded inwardly to form bottom walls 5 extending in a plane parallel with that of the top of the link with their edges abutting in a close seam 6, see Fig. 4. As indicated in Fig. 6, the sides 4 are first bent to stand at right angles to the top of the link and then folded on a line represented at $\alpha-\alpha$ to form the bottom walls of the link. The top 3 of the link 2 is extended slightly between the ends of its sides 4 and bottom walls 5 and then folded at right-angles to provide the end closures 7. The end closures 7 are thus spaced a slight distance away from the edges of the sides and bottom walls of the link to provide an opening for receiving the end-strips of the connecting-link 10 which is of a construction as next described.

Referring to Fig. 5, the connecting-link 10 is constructed from a flat sheet-metal blank stamped out to provide two relatively narrow, parallel cross-bars 11 joined at their ends by the strips 12. The cross-bars 11 are bent or folded at their opposite ends to bring the end strips 12 into planes at right-angles to the main plane of the bars.

In assembling the elements to form the strap, band or linkage, the connecting-link 10 is placed in position straddling the sides 4 of two adjacent box-link elements 2. Usually one or both of the bottom walls 5 of the box-link 2 is left without being folded in order to facilitate placing the connecting-links in straddled relation thereon. In some cases one side of the box may be folded over as shown in Fig. 6 and the connecting-link 10 hooked into place thereover while on the next succeeding box it will be placed over the unbent side which is indicated in Fig. 6 as standing in perpendicular relation to the top 3 of the box. In assembling the units the

connecting-link 10 is turned over or inverted from the position shown in Fig. 5 so that when it is placed in straddled position on the sides of two adjoining box-links 2 its cross-bars 11 will lie flat against the under side of the top of the box-link. That is to say, Fig. 5 illustrates the connecting-link 10 in the position which it assumes when the bracelet is right side up; whereas Fig. 6 shows the box-link in inverted position or turned over with its bottom side up.

After the connecting-links 10 have been assembled with the box-links 2 in the manner as above explained, the bottom walls 5 of the box are folded over to bring their longitudinal edges in abutting relation as shown in Fig. 4, with the cross-bars 11 held closely between the top and bottom of the box. With this association of the elements the end-strips 12 on the connecting-link 10 will be disposed in the openings between the ends of the sides and bottom walls of the box-link and its end closures 7. The end walls 7 of the box-links 2 are thus caused to completely cover and conceal the joints between the connecting-links 10 and the box-links, thereby giving an extremely smooth, finished appearance to the edges of the strap, band or linkage as indicated in Fig. 1. Referring to Fig. 3, a slight space intervenes between the adjoining edges of the end walls 7 of the several box-links of the band so that the link-elements may be canted slightly one in relation to another to flex the whole linkage in the manner as illustrated in Fig. 1.

It will be observed from the above that my invention provides a particularly simple and ingenious form of construction for connecting the several box-links of the band in close association while allowing the flexing of the whole linkage. Through the improved arrangement of the overlapping flaps or closures 7 at both ends of the box-link 2 the joints between the boxes and their connecting-links are entirely covered so as to conceal the mechanical construction of the bracelet as viewed from the top or along its sides.

The improved construction as herein shown and described not only provides for greater neatness and a more finished appearance of the whole band or bracelet, but further makes for greater simplicity and economy in the manufacture of the linkage. Moreover, the improved construction shown and described is particularly strong and sturdy to render the bracelet or other article durable in use with its elements not liable to become disjoined or stretched apart.

While I have herein shown and described a preferred embodiment of the device it is to be understood that various modifications may be made in the structure and arrangement of its parts without departing from the spirit or scope of the invention.

Therefore, without limiting myself in this respect, I claim:

1. A flexible strap, band or linkage comprising a plurality of outer box-like link-elements having top, side, bottom and end walls, the end walls being spaced away from the ends of the side and bottom walls to provide openings therebetween at both ends of the link; and inner connecting-links having transverse bars connected by end strips occupying planes at right-angles to the plane of said transverse bars; the inner links being straddled across the adjacent side walls of adjoining outer box-links between the top and bottom walls thereof with their end strips disposed within the openings between the ends of the side and bottom walls and the end walls of the outer box-link and covered by the top wall thereof, whereby the connecting-links are completely concealed from view on the top and sides of the linkage.

2. A flexible strap, band or linkage comprising a plurality of outer box-like link-elements each having a top wall, sides folded downwardly therefrom and end walls folded downwardly from the top in spaced relation with respect to the ends of the side walls to provide openings through the sides of the box-link at both ends thereof; and inner connecting-links having parallel cross-bars joined by end strips bent at right-angles to the plane of the cross-bars; the side walls of the box-links being inserted through the openings between the cross-bars of the connecting-links and folded therearound to connect the parts in articulated relation with the end strips of the connecting-links disposed within the openings at the ends of the box-links and covered by the top and end walls thereof whereby the inner links are enclosed and completely concealed from view on the top and sides of the linkage.

3. A flexible strap, band or linkage comprising a series of box-like link-elements having top walls, sides bent at substantially right-angles thereto and folded inwardly to provide bottom walls, with end walls bent downwardly from the top of the boxes; and connecting-links comprising parallel bars joined by end strips extending in planes at right-angles to the plane of the bars; the box-links being joined in series by the connecting-links straddling their side walls and the end strips of the connecting-links being disposed in the space between the edges of the side and bottom walls and the end walls in parallelism to said end walls of the box-link whereby to cover the joints and conceal the connections between the parts.

In testimony whereof I affix my signature.

CHARLES H. KESTENMAN.
